UNITED STATES PATENT OFFICE.

ERASTUS E. WINKLEY, OF LYNN, MASSACHUSETTS, ASSIGNOR TO UNITED SHOE MACHINERY CORPORATION, OF PATERSON, NEW JERSEY, A CORPORATION OF NEW JERSEY.

HEEL-BUILDING MACHINE.

Application filed November 25, 1918, Serial No. 263,994. Renewed May 28, 1923.

To all whom it may concern:

Be it known that I, ERASTUS E. WINKLEY, a citizen of the United States, residing at Lynn, in the county of Essex and State of Massachusetts, have invented certain new and useful Improvements in Heel-Building Machines; and I do hereby declare the following to be a full, clear, and exact description of the invention, such as will enable others skilled in the art to which it appertains to make and use the same.

This invention relates to automatic heel-building machines, and it has special, but not exclusive, reference to such machines as are adapted to build pasted heels or heel-blocks of tapered form from polygonal lifts that are cut from strips of leatherboard or other analogous sheet material.

Heretofore, when tapered heels have been manufactured, either by means of automatic heel-building machines or by the customary hand-processes, a series of graded lifts have been dinked out by means of numerous dies of the desired size and shape. These dies are difficult and expensive to make and to maintain in sharp working condition, and moreover involve a considerable expenditure of money inasmuch as a large number of dies of different sizes and forms must be kept in stock in order to meet the requirements of various styles and sizes of shoes.

It is an object of the present invention to produce an automatic heel-building machine which shall be relatively inexpensive to operate and maintain by reason of the employment of simple straight cutting knives for producing lifts of polygonal form, such as are utilized in the method of building heels set forth in Patent No. 1,285,532, granted November 19, 1918, on an application Serial No. 872,989, filed November 19, 1914, by the present applicant, and which shall therefore obviate the disadvantages attendant upon the usual prior methods of manufacture.

Accordingly, one of the features of the present invention resides in an automatic heel-building machine in which a plurality of strips of sheet material are fed to a straight cutting knife, or a plurality of such knives, which operates to concurrently cut off a series of graded polygonal lifts therefrom. These lifts are then coated with paste, after which they are transferred to a

position above an assembling table where a traveling collector effects their successive deposition and collection in the form of a tapered and stepped heel-block.

Other objects of the invention and features by which they are attained will become apparent to those skilled in the art from the following description of the preferred embodiment of the invention illustrated in the accompanying drawings, in which:

Figure 1 is a view in front elevation of a machine constructed in accordance with the present invention; Fig. 2 is a view in side elevation of the machine shown in Fig. 1; Fig. 3 is a perspective view of a heel-block which is the resulting product of the machine; Fig. 4 is a perspective view of a portion of a paste pot; Fig. 5 is a view, partially in section and partially in side elevation, of a clamping device for securing the paste pot in position; Fig. 6 is a perspective view of a portion of a skeleton frame for supporting the lifts or pieces that are cut from strips that are fed from the magazines; Fig. 7 is an enlarged view in rear elevation of one end of the machine; Fig. 8 is an enlarged view, partially in section and partially in elevation, of the connection which mechanically associates the rack for operating the paste applying plates with the actuating mechanism therefor; Fig. 9 is an enlarged view, partially in section and partially in front elevation, of one end of the machine, showing particularly the construction of one of the guide posts and of the reciprocating beam which is mounted thereon for supporting the cutting knife; Fig. 10 is a plan view of said guide post and a portion of the reciprocating beam illustrated in Fig. 9; Fig. 11 is an enlarged perspective view of the rear end of the machine, certain parts being broken away to show particularly the construction of the adjustable stops and detectors; Fig. 12 is a plan view on an enlarged scale of the strip picker by means of which the strips are fed from the magazines; Fig. 13 is a view on an enlarged scale, partially in section and partially in side elevation, of a portion of the strip picker mechanism and detecting mechanism; Fig. 14 is an enlarged view, partially in section and partially in side elevation, taken on the section line 14—14 of Fig.

1 showing the pasting apparatus and the cutting knife in their lowered positions and the lift pickers in position to transfer the cut lifts; Fig. 15 is an enlarged view, partially in section and partially in elevation, of the lift carrier in its receiving position; Fig. 16 is an enlarged view in front elevation of the central portion of the machine, illustrating particularly the pasting apparatus and the mechanism for effecting its actuation; Fig. 17 is an enlarged view, partially in section and partially in side elevation, taken on the line 17—17 of Fig. 1, showing the receiving table and collector device, and the pasting apparatus in a partially raised position, the lift carrier occupying an intermediate position in its travel toward its receiving position; Fig. 18 is an enlarged view in front elevation of one end of the machine, showing the lift carrier in its delivery position above the receiving table and the collector in the act of receiving the first lift; Fig. 19 is an enlarged vertical sectional view of one of the pickers that forms a part of the lift carrier; Fig. 20 is a horizontal sectional view of one of the carrier pickers shown in Fig. 19; Fig. 21 is an enlarged plan view of the receiving table together with the collector and its operating mechanism; Fig. 22 is a view in front elevation of a portion of the apparatus shown in Fig. 21; and Fig. 23 is an enlarged view in end elevation of the operating cams and a portion of the mechanisms actuated thereby.

Referring to the drawings and particularly to Figs. 1, 2 and 14, the machine shown comprises, in general, a supporting frame upon which the various mechanisms of the machine are mounted; a plurality of magazines 30 for containing stacks of strips of sheet material upon which the machine is adapted to act; a plurality of reciprocating strip pickers 32 for respectively feeding the strips in the several magazines step-by-step to the cutting knife; a plurality of adjustable rigid stops or back gages 34 against which the respective strips are advanced by the strip pickers and for determining their positions beneath the cutting knife; a plurality of detectors 36 for intermittently determining the exhaustion of the strips being fed to the cutting knife; a cutting knife 38 which is reciprocated periodically to concurrently cut lifts or pieces from the several strips of sheet material that are advanced and positioned against the respective stops 34; a plurality of skeleton frames 40 for supporting the lifts or pieces that are cut from the respective strips; a plurality of lift pickers 42 for concurrently seizing the cut lifts and transferring them to the supporting frames; a lift carrier 44 adapted to be swung from a receiving position above the supporting frames to a delivery position

over the assembling table; a pasting apparatus 46 disposed beneath the supporting frames and adapted to apply paste to the under sides of the lifts supported thereon and to raise the lifts into position to be seized by the lift carrier in its receiving position; an assembling table 48 upon which the lifts are deposited from the lift carrier in its delivery position; and a traveling collector 50 movably mounted upon the assembling table 48 and adapted to successively release the several lifts held by the lift carrier over the table and to collect them in the form of a heel pile and effect their discharge. 80

The various component mechanisms of the machine are supported upon the frame which comprises a plurality of side frames 54 and 56 (Figs. 1 and 2) upon which are mounted a horizontal table 58 for supporting the magazines 30 and the assembling table 48 upon which the heel-piles are assembled. The frame also comprises a front frame member 60 and a back frame member 62 which rigidly connect the side frames 54 and 56 and with them form a substantially rectangular frame structure. Intermediate the front and rear frame members 60 and 62 and rigidly connecting the side frames 54 and 56 is a cross brace 64 which supports a slotted plate 66 which constitutes an extension of the magazine table 58 and said brace also carries a removable cutting block 68 with which the cutting knife 38 cooperates. Another cross brace 70 is disposed intermediate the front and rear frames 60 and 62 and serves to support and guide the pasting apparatus 46, while a cross-brace 72 is positioned between the magazine table 58 and the cross brace 64 and is provided with a slotted plate 74 which aids in supporting the magazine table 58. 100

The side frames 54 and 56 are provided with suitable bearings for receiving a power shaft 76, a cam shaft 78 and a rocker shaft 80, while a plurality of short auxiliary shaft sections 82 and 84 are suitably mounted in bearings carried by the intermediate cross frame or brace 70. 110

The power shaft 76 is provided with a fast pulley 86 and a loose pulley 88 with which a suitable belt cooperates in the usual manner to supply power to the machine. The power shaft 76 is provided near its respective ends with pinions 90 that mesh with cooperating gears 92 which are fixed to the cam shaft 78, the latter being provided with a plurality of cams 94, 98, 100, 102, 104 and 106 and with a plurality of eccentrics 110 at the respective ends thereof. 120

The auxiliary shaft sections 82 and 84 are respectively provided with gears 114 that mesh with suitable gears 116 that are fixed to the cam shaft 78 and by means of which the auxiliary shafts 82 and 84 are driven. 130

The various operating levers and bell cranks that cooperate with the several cams of the machine for effecting the actuation of the component mechanisms thereof are 5 mounted on the rocker shaft 80.

Having described the general construction of the main supporting frame of the machine, together with the mode of mounting certain of the main shafts thereof, consideration will be given to the various devices and mechanisms which go to make up the machine as a whole.

The various magazines 30 (Figs. 7, 11 and 14), which contain the several stacks of strips from which lifts are cut and subsequently assembled to form a heel-pile, severally comprise a pair of side-supporting plates 118 that are disposed and rest upon the magazine table 58. The lower rear corners of the plates 118 are provided with downwardly-projecting members 120 having screw-threaded bosses 122 integrally associated therewith. Co-operating with these bosses on each set of plates is an oppositely threaded bolt 124 that is positioned midway between its ends by a lug 126 which projects laterally on the center-line of the adjacent magazine from the magazine table 58 and which is located between enlarged 20 portions 127 provided on said bolt. Similarly, the upper forward corners of the several plates 118 are provided with bosses 122 (Fig. 7) and screw-threaded bolts 124 of like construction.

35 The forward ends of the magazines are closed by a single plate 128 that is provided with a plurality of upwardly projecting hooked members 130 (Figs. 7 and 14) that are located above the center-lines of the magazines and which partially surround the bolts 124 between the enlarged portions 127. The various bolts 124, embodied in the magazine construction just described, are employed for the purpose of adjusting the 40 spacing of the plates 118 of the several magazines whereby said magazines may be adapted to accommodate stacks of strips of any desired widths.

The lower portion of the end plate 128 is provided with a plurality of vertically 45 adjustable angle members 132 (Fig. 14) that are bolted thereto and which severally carry a plurality of plates 134, the latter being located on the center-lines of the several magazines for holding down the strips as they are fed and for maintaining them under control. Obviously, if heel-piles of tapering form, such as illustrated in Fig. 3, be built, the strips employed in the several 50 magazines must be of graded widths, and the adjustable magazines just described permit of accommodating stacks of strips of any desired gradations.

The lowermost strips in the several magazines 30 are fed forwardly beneath the

holding down plates 134 to the cutting knife 38 in a series of steps by means of the strip pickers 32 (Figs. 2 and 14) which are severally disposed directly beneath each of the magazines and which are periodically reciprocated to feed the strips in the manner desired. Each of the strip pickers 32 is provided with a plurality of end prongs 136 (Fig. 12) which are projected into the lowermost strip in the magazine when the reciprocating picker is advanced, whereby the strip is fed forwardly until it engages its stop or back gage 34. As the strip picker is moved backward, the prongs are withdrawn from the strip and the strip is left 75 in proper position to be cut by the cutting knife 38.

The construction and operation of the strip pickers 32, the gages 34 and the detectors 36 is similar to that shown, described and 80 claimed in Patent No. 1,352,492, granted September 14, 1920, on a co-pending application Serial No. 143,738, filed January 22, 1917, by the present applicant, and therefore no detailed description thereof is deemed 85 necessary, reference being had to said patent for a full and complete description of the structure and operation of the apparatus.

Briefly, each strip picker 32 (Figs. 12 and 14) is pivotally mounted on a reciprocating carrier 138 which is suitably supported beneath the magazine table 58 and is actuated to and fro by means of an arm 140 (Fig. 2) which is rotatively mounted on a 90 rocker shaft 142 and which is connected by a yielding coupling 144 to an arm 146 that is fixed to the shaft 142. The shaft 142 is provided substantially at its middle with a fixed arm 148 that is connected by means of a link 150 with an arm 152 of a lever that is rotatively mounted on the rocker shaft 80 and is provided with another arm 154 that carries at its outer end a roll 156 that 95 cooperatively engages a cam path in the face of the cam 102. This cam 102 is designed to effect the periodic oscillation of the shaft 142 and the arms 146 that are fixed thereto.

Inasmuch as all of the strip pickers 32 are connected through the arms 146 to the 100 shaft 142 in the manner just described, it is evident that all of the strip pickers are 105 adapted to be actuated concurrently to effect the advance of the lowermost strips in the several magazines. The strips are fed forwardly until their movement is arrested by their engagement with the several rigid stops or back gages 34, whereupon sufficient pressure is imposed upon the yielding couplings 144 to effect their independent disconnection, so that, although the operating arms 146 continue to be actuated no further movement of the strip pickers 32 is produced.

The back gages or stops 34 constitute the 110 ends of a series of levers 158 (Figs. 2, 11, 115

and 14), each of which extends rearwardly and is pivotally attached to an adjustable rack 160 which cooperates with a pinion 162 that in turn engages a rack 164 associated with an arm 166, the end of which constitutes one of the detectors 36. By reason of the interposition of the pinion 162 between the adjustable racks 160 and 164, the position of the back gage or stop 34 and the detector 36 may be concurrently and proportionately determined. The several back gages or stops 34 are periodically raised into operative position to perform their intended functions by means of links 157 (Figs. 1, 2 and 23) that are severally connected between the respective levers 158 and a plurality of arms 159 that are fixed to a longitudinally disposed shaft 161. The shaft 161 is connected to and operated by the cam 100 by means of an arm 163 that has a lost-motion connection to a bell-crank 165 carrying a roll that cooperatively engages the cam.

The purpose of each of the detectors 36 is to periodically feel of the strip that is being advanced to the cutting knife in order to determine its exhaustion or whether or not there is sufficient material left in the strip from which to cut a piece or lift of the desired dimensions. In order to determine this fact, it is necessary that the detector 36 be positioned a distance ahead of the cutting knife 38 which is equal to the distance at which the stop 34 is placed beyond it, as will be understood. Thus, if during the detecting operations of the detector 36, it is found that the strip is exhausted or that it is so short that it has passed beyond the detector, the operation of the strip picker 32 is so modified as to cause it to engage and advance a new strip from the bottom of the stack. If, on the other hand, the detector 36 engages a portion on the strip during its detecting operation, in which case there is sufficient material for a full size lift to be cut, the operation of the strip picker continues without modification and the picker acts intermittently upon the strip being advanced until said strip is used up or is reduced in length to such an extent that another full size lift cannot be cut.

Since the construction and operation of the back gages or stops and detectors form no material part of the present invention and are described and illustrated in full in the above mentioned Patent No. 1,352,492, no further description thereof is deemed necessary, except in so far as the concurrent and graduated adjustment of the detectors 36 and stops 34 is rendered possible through the agency of an improved construction with which the present machine is provided, and which will now be described.

In building tapered heel-piles or blocks, as illustrated in Fig. 3, it is clear that the lifts of which they are composed are graded

in width as well as in length. The proper lengths of the lifts that are produced from the strips in the various magazines are determined by the widths of the strips themselves, but the width of the lifts cut therefrom are determined by the extent to which the strips are advanced during their feeding movement, which in turn is fixed by the positions of the several stops or back gages 34. It is necessary therefore to adjust or set those stops or gages 34 in accordance with the widths of the lifts to be cut, and hence said stops are set at varying and graded distances with respect to the cutting knife and the respective magazines so that the lengths of the feeding movements of the several strips are graduated to insure that lifts of the desired graded widths shall be cut from several strips.

In order to effect this adjustment of all the stops 34 by a single operation, each of the racks 160 at the respective ends of the machine is provided with a bracket 170 into which is screw-threaded an adjusting rod 172 (Fig. 11) that projects through a suitable opening in the rear frame member 62 and is provided with a knurled head 173 by means of which it is adjusted to vary the position of the associated rack 160, and, therefore, of the stop 34 and detector 36 connected thereto. A bar 174 is connected by means of bolts 176 and nuts 178 to each of the adjustable racks 160 whereby all of the stops and detectors are interconnected and correlated.

To concurrently and proportionately set the gages 34 and the associated detectors 36 for building a tapered heel-block of any desired pitch or formation, it is therefore only necessary to adjust the two end racks 160, by means of the adjusting rods 172, so that the distance A from the end of one of the end racks 160 to the rear finished face 180 of the frame member 62 shall be equal to the desired width of the largest lift in the heel to be built and so that the corresponding distance at the other end of the machine shall be equal to the desired width of the smallest component lift. Having effected this adjustment in the manner described, the intermediate stops 34 and detectors 36 will be properly and proportionately adjusted by reason of the interconnecting bar 174 so as to insure the cutting of a series of lifts of proper graduated widths to produce a heel-block of the desired form and pitch.

The cutting knife 38 which concurrently cuts lifts of graded sizes from the several strips that are fed into position against the respective stops or back gages 34 is reciprocated periodically during the operation of the machine. The knife 38 is of ordinary form and conveniently comprises a plurality of sections, as shown in Fig. 9, which are secured to a reciprocable beam 184 by means of bolts 185. The beam 184 is slidably

mounted at its respective ends upon a plurality of hexagonal posts 186 (Figs. 2, 9 and 10) which are set into the upper ends of the side frames 54 and 56 and which are rigidly positioned by means of binding braces 188 that are provided with openings to receive the upper ends 189 of the posts 186. The binding braces are bolted or otherwise secured to the upper ends of pedestal members 190 that project upwardly from the respective side frames 54 and 56. In order to take the wear occasioned by the reciprocations of the beam 184, said beam is provided with renewable gibs 191 (Fig. 10).
 15 The ends 187 of the beam 184 project outwardly beyond the guide posts 186 and respectively carry pins 192 to which substantially vertical operating rods 194 are pivotally connected (Figs. 2 and 9). The operating rods 194 are disposed outside the respective side frames 54 and 56 and their lower ends are pivotally connected to crank pins 196 that are carried by the eccentrics 110 which are secured to the respective ends 25 of the cam shaft 78.

From the foregoing description, it is manifest that, as the cam shaft 78 is continuously rotated, the beam 186 and the associated cutting knife 38 are periodically reciprocated to cut lifts of predetermined dimensions from the strips that are intermittently fed into cutting position against the stops 34.

As the knife 38 descends into its cutting position to sever a row of lifts from the strips, it cooperates with the cutting block 68 (Fig. 14) which is supported in position beneath it on the cross brace 64 by means of a clamping member 200 and a plurality of bolts 202.

The reciprocating beam 184 carries a plurality of spring-cushioned ejecting pins 203 which, in the lowered position of the knife, project through openings 205 in the holding down plates 134 into engagement with the strips. If the strips are sufficiently long to be supported upon the detectors 36, said ejecting pins yield upwardly against their springs, but if any strip is too short for another full-sized lift, the pin pushes the remnant end thereof downwardly and effects its ejection.

Having cut a row of lifts from the strips, said lifts are transferred across the slotted plate or table 66 and in position upon the skeleton supporting frames 40 by means of the lift pickers 42.

There are two skeleton frames 40 (Figs. 6, 14, 16 and 21) which are arranged longitudinally of the machine in end-to-end relation. Each of the frames comprises a pair of end members 204 that are provided at one end with notches 206 which are adapted to receive a rod 208 that extends longitudinally of the machine and upon which the end

members 204 rest. The other ends of the end members 204 are provided with extending fingers 210 that normally are adapted to rest upon the upper edge of the plate 66. Between the end members 204 of the respective frames are a plurality of parallel members 212 which are convergently disposed in an upward direction, and across which a plurality of members or wires 214 are secured by means of screws 216. These wires 75 serve the purpose of supporting the lifts which are transferred thereto by means of the lift pickers 42.

The lift pickers 42 are of like construction, and each embodies a substantially horizontal arm 220 (Figs. 2, 14 and 17) to the forward end of which a substantially vertical plate 222 is suitably secured. This plate 222 is provided with a plurality of downwardly projecting prongs 224 which 80 constitute the picker points for seizing the lifts that are cut from the strips of sheet material, and which rest upon the plate 66. A presser foot or stripper 226 is mounted upon a movable pin 228 adjacent the end of 85 the arm 220 and is normally maintained in its lowermost position by means of a spring 230 that surrounds said pin.

During the normal operation of the lift pickers 42, said pickers are swung to the 90 right, from the position shown in Fig. 17, until the downwardly projecting prongs of the pickers are in position over the lifts that have just been severed from the strips of sheet material. During this swinging movement the arms 220 are tilted in such a manner as to force the prongs downwardly into the lifts, whereby said lifts are impaled thereon, the presser feet 226 being thereby forced upwardly against the action of the 95 springs 230 as illustrated in Fig. 14.

The transferring return movement of the lift pickers then takes place during which the pickers are concurrently drawn in the opposite direction until the several lifts are 100 in position upon the wires 214 of the supporting frames 40. Thereupon, the arms 220 are tilted so as to raise the picker prongs 224 to permit the strippers 226 to be pressed downwardly to strip or remove the lifts 105 therefrom, whereby said lifts are deposited upon the supporting frames. The return movement of the pickers then continues until said pickers are withdrawn to the left 110 of the supporting frames, as shown in Fig. 17.

This cycle of operation is effected by means of the cooperative action of the two cams 94 and the cam 106 (Figs. 1, 2 and 23) that are fixed to the cam shaft 78, through the operating mechanisms now to be described. Since there are two duplicate sets of operating mechanisms, one for each cam 94, a description of only one of them will be given.

Traveling in the cam path of the cam 94 at the right hand end of the machine (Fig. 1) is a roller 232 which is carried at the end of an arm of a bell-crank 234 that is rotatably mounted upon the rocker shaft 80. The other arm of the bell-crank 234 is connected to a link 236 (Fig. 2) which has a pivotal connection to one arm of a bell-crank 238. Said bell-crank is mounted upon a longitudinal shaft 240 carried in the side frames 54 and 56 and its other arm has a pivotal connection with a link 242. The upper end of the link 242 is pivoted to one end of an arm 244 which is pinned to the inner end of a stud 246 carried by the frame 54, and is provided with another depending arm 248 fixed to the other end thereof. The lower end of the arm 248 is connected to the lower end of a bell-crank 250 by means of a link 252, and said bell-crank 250 is pivotally mounted upon a pin 254 that is carried by an arm 256 which is loosely mounted upon the stud 246. The other arm of the bell-crank 250 is connected by means of a link 258 to one end of an arm 259 that is rigidly secured to the right hand end of a shaft 278 that extends the full length of the machine and projects beyond the respective side frames 54 and 56. The shaft 278 serves to support and carry all of the picker arms 220 which are fixed thereto by keys 221 (Fig. 17).

The mechanisms at the respective ends of the machine, just described, serve to effect rotative movements of the shaft 278 and, therefore, the desired tilting of the picker arms 220, which are keyed thereto, whereby the picker prongs are raised and lowered in position at the proper times as determined by the cams 94.

The swinging movements of the picker arms 220 are effected through the agency of the cam 106 which cooperates with a roller 260 (Figs. 2 and 23) that is carried by one arm of a bell crank 262 which is rotatably mounted upon a rocker shaft 80. The other arm of the bell crank 262 is connected by means of a connecting rod 264 with an arm 266 that is fixedly mounted upon the longitudinal shaft 240, and the respective ends of said shaft are connected to the lower ends of rods or links 268 by means of arms 269 that are secured thereto. The upper ends of the rods 268 have pivotal connections to arms 270 that are severally fixed to the inner ends of studs 272 that are rotatably mounted upon the frames 54 and 56. Other arms 274 fixed to the outer ends of the studs 272 are pivotally associated at 275 with levers 276 intermediate their ends. The lower ends of the levers 276 have pivotal connections with pins 254 that connect the bell cranks 250 with the arms 256, while the upper ends of the levers 276 are pivotally associated

with the respective ends of the longitudinal shaft 278 to which the picker arms 220 are keyed.

This portion of the operating mechanism serves to swing the shaft 278 and its associated picker arms 220 back and forth between their rearward positions, as shown in Figs. 2 and 14, and their forward positions, as indicated in Fig. 17.

From the foregoing description it is evident that the operating mechanisms associated with the cams 94 and 106 are respectively adapted to effect the tilting and swinging movements of the picker arms whereby the row of lifts that are cut from the several strips are seized, transferred to the supporting frames 40 and subsequently deposited thereon.

Inasmuch as the present machine is intended to build pasted heels, provision is made to apply paste to all but the bottom lifts thereof. This is accomplished through the agency of the pasting apparatus 46 which is disposed beneath the skeleton frames 40 for supporting the lifts after they have been cut and transferred thereto. The pasting apparatus is operated in such manner as to coat with paste the bottom surfaces of the lifts resting upon the wires 214 of the supporting frames 40 and to subsequently raise the frames and the lifts resting thereon into such position that the lifts may be seized by the lift carrier 44 when it occupies its receiving position, as shown in dotted lines in Fig. 17.

Referring to Figs. 1, 2 and 16, the pasting apparatus comprises a plurality of paste pots 282 and 284 that are disposed longitudinally of the machine in end-to-end relation and beneath the supporting frames 40. A plurality of paste pots are employed in lieu of a single one merely for purposes of convenience in removing them to be cleaned. The paste pots 282 and 284 are detachably mounted in a manner to be set forth upon a movable supporting frame 286 which is carried by a plurality of operating rods 288 that project loosely through suitable guide openings in the cross brace 70. The lower ends of the operating rods 288 are pivotally connected by means of pins 290 (Figs. 2 and 23) to the upper ends of a plurality of links 292, the lower ends of which are provided with elongated slots 294 which are adapted to receive the respective crank pins 296 that are carried by crank arms 298 secured to the opposite ends of the auxiliary shafts 82 and 84. As the shafts 82 and 84 are continuously rotated in the manner already set forth, the crank pins 296 cooperate, through the pin-and-slot lost-motion connections just described, to effect the periodic reciprocation of the movable supporting frame 286 and the paste pots mounted thereon. The provision of the pin-

and-slot lost-motion connections is for the purpose of permitting the paste pots 282 and 284 and the supporting frame 286 to temporarily rest upon the supporting and 5 guiding cross brace 70 when the paste pots occupy their lowered positions, as will be understood.

Being of like construction, a description of a single paste pot will suffice. The paste 10 pot 284 (Figs. 4, 5 and 14) is of rectangular trough-like construction and its base 302 is provided with suitable outer grooves to receive inwardly projecting guide members 304 that are associated with the movable 15 supporting frame 286. Thus, a dove-tail way construction is provided which permits the paste pot to be slid into and out of position longitudinally. For the purpose of firmly securing the paste pot to the supporting 20 frame 286, a gib or bar 306 is provided between the base portion 302 of the paste pot and the adjacent portion of the supporting member 286, and this gib is clamped tightly against the base portion 302 by 25 means of a plurality of clamping bolts 308 which are provided with laterally projecting pins 310 for convenient manipulation.

In order to apply paste to the under surfaces of the lifts resting upon the supporting wires 214 of the frames 40, the paste pot is provided with a plurality of paste applying plates 312. These plates, with the exception of the one at the right-hand end of the machine which acts upon 30 the first or bottom lift of the heel, are rotatively mounted in such manner as to be periodically immersed in the paste within the paste pot. Each of the paste applying plates 312 is provided with side lugs 314 that are pinned to a supporting rod 316 which projects laterally across the paste pot and has its bearings in the sides thereof. The rod 316 of the right-hand paste applying plate 312 is fixed in position so 40 that the plate is always maintained in its raised position, as indicated in Figs. 4 and 18, and therefore is never immersed in the paste. Hence, the right-hand lift, which later constitutes the base-lift of the heel, is 45 not coated on its underside.

The rods 316 upon which the remaining paste applying plates 312 are secured are rotatively mounted in the sides of the paste pot and one end of each rod is provided 50 with a pinion 318. These pinions 318 mesh with a slidable rack 320 which moves longitudinally in a groove provided in a projection 322 extending laterally from one side of the paste pot. A cover 324 envelopes the 55 pinions and rack and protects them from injury.

In order to effect the longitudinal reciprocation of the rack 320, the laterally projecting member 322 is slotted throughout a 60 considerable portion of its length to permit

the movement of a slotted yoke 326 which projects downwardly through the slot in the member 322 and is secured to substantially the middle of the rack (Figs 4 and 16). The lower end of the yoke 326 projects below 65 the member 322 into such position that the end of a threaded pin 330 (Fig. 8) that is carried at the upper end of an arm 332 extends into the slot thereof. The pin 330 is provided with a knurled head 334 by 70 means of which the pin may be screwed into and out of engagement with the yoke 326. A check nut 336 is also provided for locking 75 the pin in its adjusted position. The pin-and-slot connection, just described, between the actuating lever 332 and the rack 320 is particularly intended to permit a ready disengagement of said members, when the paste pot is elevated into its uppermost position during its periodic reciprocations. 80

The lever 332 which carries the adjustable pin 330 is secured to a stud 338 (Figs. 1 and 16) that is rotatably mounted in the stationary cross brace 70. The opposite end of the stud 338 is provided with an arm 340 to the end of which a link 342 is connected. The lower end of the link 342 is associated with an arm 344 (Fig. 23) of a bell crank by means of a universal connection 346. This bell crank is rotatively 90 mounted on the rocker shaft 80 and its other arm 347 is provided with a roll 348 that engages a cam path on the cam 104.

The cams 104 are designed to effect the periodic reciprocations of the racks 320 100 whereby the paste applying plates 312 are accordingly immersed in the paste pots at each cycle of operation of the machine and are brought into their normal horizontal positions above the paste pots just prior to the time when the paste pots are elevated. As already stated, the elevation of the paste pots effects the disengagement of the pins 330 from the slotted yoke members 326 by 105 means of which the racks are reciprocated. When this takes place, the respective cams 104 serve to maintain the operating levers 332 carrying the pins 330 in vertical position in order that they may be ready to again effect the operative connections between the pins 330 and the yoke members 326 when the paste pots are lowered. 115

It is necessary, however, to provide means for locking the paste applying plates 312 in their horizontal position during this movement in order that they shall properly engage and apply paste to the under sides of the lifts resting upon the wires 214 of the supporting frames 40. The inner ends of the respective racks 320 (Fig. 16) therefore, are provided with suitable openings 350 which register with and are adapted to receive locking pins 352 when the paste applying plates 312 occupy their horizontal positions. Each of the pins 352 is car- 120 125 130

ried at the end of a lever 354 that is pivotally mounted upon a pin 356 supported in a bracket 358 that is attached to the side of a paste pot. The other end of the lever 354 is normally maintained in engagement with an adjustable set screw 360 by means of a spring 362 that is positioned between said lever and a block 364 that is fastened to the side of the paste pot. The set screw 10 360 is adjustably mounted in a central bracket 366 which is carried by the stationary cross brace 70. With this construction, the various parts of the locking device, just described, occupy their released positions, as 15 shown in Fig. 16, when the paste pots are in their lowered position.

As soon as the paste pots are raised, however, the free ends of the levers 354 are disengaged from the set screws 360 and the 20 springs 362 serve to force the locking pins 352 upwardly and into the openings 350 in the respective racks. Therefore, the rotatable paste applying plates 312 are positively retained in horizontal position while the 25 paste pots are raised.

Upon the lowering of the paste pots, the set screws 360 engage the levers 354, thereby overcoming the springs 362 and withdrawing the locking pins 352 from their 30 retaining positions, whereby the paste applying plates 312 are released and permitted to be rotated downwardly and immersed in the paste pots through the action of the operating mechanism already described.

When the paste pots are raised from their lowered position, as shown in Fig. 14, the paste applying plates 312 which have just 35 been immersed in the paste are brought into engagement with the wires 214 of the supporting frames 40, and with the under surfaces of the lifts disposed thereon, as indicated in Fig. 17, the plates 312 being provided with a series of grooves 370 which are adapted to receive the wires 214. As 40 the elevation of the paste pots continues, the supporting frames 40, together with the lifts resting thereon, are raised into the position indicated in dotted lines in Fig. 17, in which position the lifts are seized by the 45 lift carrier 44 in a manner to be herein-after described.

By reason of the construction of the supporting frames 40 and their method of support, said frames are raised bodily from the supporting rod 208 and the plate 66 upon which the ends thereof respectively rest. As the paste pots are lowered subsequent to the seizing of the lifts by the lift carrier 44, the supporting frames 40 are also lowered 50 until they again rest upon the supporting rod 208 and plate 66. In order to guide the supporting frames into proper positions when they are deposited, as just described, a plurality of guide members 374 (Figs. 16 and 21) are located upon the rod 208 at the

respective ends of the two supporting frames. These guide members 374 are provided with curved surfaces 376 with which the end members 204 of the frames are adapted to co-operate and which function 70 to definitely determine the position of the frames.

The lift carrier 44 which seizes the lifts, when raised in the manner just described, comprises a plurality of complemental channel members 378 and 380 (Figs. 1, 15 and 19) which extend the full length of the machine and which are secured at spaced intervals to a plurality of spacing members 382 (Fig. 18). The carrier frame, thus 80 formed, is provided with a plurality of spaced pickers such as shown in Figs. 15 and 19. These pickers are located in alignment with the several magazines so that they are properly positioned to seize the 85 several lifts that are raised by means of the reciprocating paste pots.

Referring to Figs. 15, 19 and 20, each of these pickers comprises a rod 388 that is slidably mounted in vertical position in the channel members 378 and 380 comprising the carrier frame. The lower end of each rod 388 is provided with a stripper plate 390 having openings 392 therein to permit the passage of a corresponding number of 95 picker prongs in the form of pointed members 394 upon which the lifts are impaled through the action of the reciprocating paste pots. Surrounding the rod 388 is a collar 396 that is pinned thereto and which serves to limit the downward movement of the stripper 390 by engagement with the lower channel member 378. A coil spring 398 surrounds the upper end of the rod 388 and acts against the collar 396 to normally 105 maintain the rod and its associated stripper plate 390 in its lowermost position.

The picker prongs 394 are suitably secured to a plate 400 which is fastened to the lower surface of the lower channel member 110 378 by means of screws 402. The plate 400 is also provided with an upwardly extending portion 404 (Figs. 18 and 20) which is disposed against the front face of the lower channel member 378 and is fastened there- 115 to by means of screws 406. The plate 400 is provided at its rear corners with notches (Fig. 20) to accommodate the screws 402, and at substantially the middle of its rear portion it is provided with a recess 408 to 120 permit the passage of the rod 388. A tongue member 410 projects rearwardly from the plate 400 and into a slot 412 that is provided in the rod 388 whereby said rod is prevented from turning although permitted to 125 be raised and lowered in position.

When a lift is raised and impaled upon the picker prongs 394 by the elevation of the paste pots, the stripper plate 390 is forced upwardly against the action of the spring 130

398 and, in order to retain said plate in its raised inoperative position, each of the picker devices is provided with a latch 414 (Figs. 15 and 19) which engages beneath 5 a flange 416 on the collar 396 when said collar is pushed upwardly during the impaling operation. This latch 414 is secured to a rod 418 that is rotatively mounted in the side members of the lower channel member 10 378 and is normally urged into its latching position by means of a spring 420. The forward end of the rod 418 projects through the channel member 378 and is provided with a trip member 422 (Figs. 15, 18 and 15 20) pinned thereto, by means of which the latch 414 is subsequently released to permit the spring 398 to force the stripper plate 390 downwardly and thus strip off and discharge the lift seized or impaled by the 20 picker prongs.

During the operation of the machine, the lift carrier 44 with its several associated picker members is swung from a receiving position, shown in Fig. 15, in which the several lifts are seized, to a delivery position, shown in Fig. 2, in which the lift carrier is located above a portion of the assembling table 48 and in which position the lifts are released and deposited upon the table in 30 a manner to be hereinafter described.

In order to effect this swinging movement of the lift carrier and to maintain it in vertical position throughout its actuation, a parallel-motion mechanism is employed and will now be set forth. Referring particularly to Figs. 2 and 18, the lift carrier frame is pivotally mounted at its respective ends upon the corresponding arms 426 of a pair of similar three-armed levers that are respectively pivotally mounted upon studs 428 which are carried by brackets 430 constituting parts of the several binding braces 188 which serve to hold the hexagonal guide posts 186 in position. Another arm 432 of 40 each of the three-armed levers, just referred to, is connected to one end of an arm 434 of a bell-crank by means of a link 436. This bell crank is rotatively mounted on a pin 438 carried by a bracket 430 and its other arm 440 has a pivotal connection 442 to an upwardly projecting lug 444 that is secured to the carrier frame.

The lengths of the arms 426 and 440 and the locations of the pivotal connections thereof with the carrier frame and with the bracket 430 are such that a parallel-motion mechanism is provided which insures that the lift carrier and its associated pickers is maintained in a vertical position throughout 55 its movement.

Each of the three-armed levers, already referred to, embodies a third arm 446 which is connected by means of a link 450 to one arm of a bell-crank 452, the other arm of 60 which has a pivotal connection with the

upper end of a connecting rod 454. The lower end of the connecting rod 454 is pivotally associated with an arm 456 that is fixed to the rocker shaft 80.

The rocker shaft 80 is periodically rotated 70 through the agency of an arm 458 (Figs. 1 and 23) that is fixed thereto at substantially the middle thereof and which carries at its outer end a roll 460 that co-operatively engages a cam path in the cam 98. The cam 75 98 is designed to effect periodic rotative movements of the rocker shaft 80 whereby the lift carrier 44 is swung from one of its operative positions to the other through the 80 operation of the actuating mechanisms just described.

The lift carrier 44 is definitely located in its receiving position by means of a plurality of notched stop arms 459 (Figs. 15 and 17) that project forwardly from a supporting 85 channel member 461 that extends longitudinally of the machine and is secured to the upright pedestal members 190 of the respective side frames. These stop arms 459 are engaged by position-limiting rods 90 462 that are mounted between brackets 463 which project upwardly from the upper channel member 380 of the carrier frame.

Having seized the several lifts in its receiving position by reason of their being impaled upon the picker prongs 394, the lift carrier 44 is swung into its delivery position, shown in Fig. 2, in which it retains the lifts until they are subsequently and successively 95 released and collected in the form of a heelpile or block by means of the traveling collector 50, the construction and operation of which will now be set forth.

The collector 50 (Figs. 17, 21 and 22) 105 is substantially U-shaped in plan, being provided with side members 464 and 466 and a slightly inclined rear member 468. The side member 466 is materially extended and carries at its left-hand end a roll 467 that is adapted to travel in a substantially elliptical endless groove 470 in the assembling table 48 and which constitutes a track for guiding and positioning the collector 50. The other end of the extended side member 466 is pivotally connected by means of a pin 472 to an endless chain 474 which is carried upon sprockets 476 and 478 that are rotatively mounted beneath the respective 110 ends of the assembling table 48. Upon the same shaft 480 that carries the sprocket 476 is another sprocket 482 with which a chain 484 cooperates. This chain 484 is also carried upon a sprocket 486 that is mounted on a vertical shaft 488.

The shaft 488 has a thrust bearing 490 that is supported by the front frame 60 (Fig. 22) and the lower end thereof is journaled in a bracket 492 (Figs. 1 and 2) that is associated with said front frame. A mitre 115 120 125 130

gear 494 is secured to the lower end of the shaft and cooperates with a mitre gear 496 that is carried by a shaft 498 which is mounted in the lower end of the bracket 492. The other end of the shaft 498 is provided with a mitre gear 500 (Fig. 2) which meshes with a large mitre gear 502 that is fixed to the auxiliary shaft 82.

The continuous rotation of the auxiliary shaft 82 causes the chain 474 to which the collector 50 is attached to be continuously operated through the intermediate connections just described. Thus, the collector 50 is continuously moved along the table 48 from its initial operative position at the right-hand end thereof, as indicated in Fig. 18, and during this movement an upwardly projecting member 504 mounted thereon is successively brought into engagement with the several tripping members 422 of the respective pickers that constitute parts of the lift carrier. As the member 504 engages these tripping members 422, the respective latches 414 are successively released, whereby the stripper plates 390 of the several pickers are forced downwardly to strip off the lifts seized by and impaled upon the picker prongs 394. Said lifts are thereby successively deposited and collected in superposed relation upon the table 48 as they fall from the lift carrier by means of the traveling collector 50.

Having collected the freshly pasted lifts into the form of a heel-pile or block, said block is discharged from the collector at the left-hand end of the assembling table 48 in the following manner:

Inasmuch as the component lifts of the heel-block are freshly pasted, they are subject to ready disarrangement and, therefore, it is necessary to avoid any undue shocks that might occasion the dislocation of the lifts. For this purpose, the operation of the collector 50 is so prescribed that it moves the completed assembled heel-block into its discharging position at the left-hand end of the assembling table 48, as indicated in dotted lines in Fig. 21, and thereafter merely withdraws or recedes, thereby gently leaving the heel-block resting in its discharged position.

To discharge the heel in this manner, it is found desirable to provide means for maintaining the collector 50 in substantially the same relative position throughout its length of travel; and this result is accomplished by the aid of a gate or switch member 508 that is pivotally mounted upon a pin 510 at the left-hand end of the track. Said switch member 508 is normally maintained in the position illustrated in Fig. 21 by means of a spring 512 and, when in this position, the rounded end portion 514 of the track 470 is closed while a branched groove or track 516 is opened to receive and guide the roller

467 at the forward end of the collector 50. This roller, therefore, traverses the branch track 516 and, after passing the pivotal point 510 thereof, it forces the switch member 508 in a counter-clockwise direction against the action of the spring 512 thereby causing the switch member to be turned into such a position that it closes the branch track 516 and opens the circular track portion 514. Thus, the pin 472 which connects the collector 50 with the chain 474 is permitted to traverse the curved track portion 514 thereby maintaining the collector 50 in substantially the same position which it occupies as it traverses over the assembling table 48 and collects the component lifts of the heel-block from the lift carrier. The assembled heel-block, therefore, is brought into the position indicated in dotted lines in Fig. 21, at the left-hand end of the table 48.

As the chain 474 continues its movement, the collector 50, by reason of its pin connection 472 therewith, is drawn around the curved portion 514 of the track, during which movement the roller 467 having passed beyond the switch member 508 is permitted to traverse the branch track portion 518 which is formed as soon as the switch member 508 is restored to its initial position, as indicated in Fig. 21. The direction of movement of the collector 50, therefore, is reversed as it rounds the end of the track, while by reason of the peculiar construction thereof it is maintained in substantially the same relative position, whereby the collector is merely withdrawn in approximately the opposite direction from that in which it is advanced as the heel-block is collected. The freshly pasted and completed heel-block, therefore, is discharged from the collector without jar or shock and is left lying upon the table where it may be carefully removed by the operator and placed in a heel-press if desired.

Adjacent the other end of the track 470 is an auxiliary groove or track portion 520 which is disposed angularly between the straight portions of the main track for the purpose of returning the collector 50 to its proper position at the right-hand end of the assembling table 48. This operation is effected by means of a plurality of switches 522 and 524 that are respectively pivotally mounted on pins 526 and 528 which are normally maintained in their closed positions, as illustrated in Fig. 21, by means of the respective springs 530 and 532. In these positions, both ends of the angularly positioned track portion 520 are closed; so that as the collector 50 is being withdrawn with its pivotal connection with the chain 474 in advance, the pin 472 is caused to traverse the straight portion of the track, and by its engagement with the tail-piece 534 of the switch 522 to effect its opening. There-

fore, as the roller 467 reaches the switch member 522 it is deflected into the angularly disposed track portion 520. As the chain 474 continues to move, the pin 472 travels around the curved track portion 536 while the roller 467 passes through the track portion 520 thereby opening the switch 524 and causing the collector to resume its position as indicated in Fig. 18.

19 As the machine continues to operate, the cycle of operations is repeated, during each of which a heel-block is produced in the manner set forth.

Obviously the construction and operation 15 of the machine may be materially varied from that shown and described without departing from the spirit and scope of the invention and, therefore, only such limitations should be imposed as are indicated in the 20 appended claims.

Having shown and described the preferred embodiment of the invention, what is claimed as new is:

25 1. A heel-building machine having, in combination, means for feeding strips of sheet material, a reciprocable straight knife for cutting a series of polygonal lifts therefrom, means for superposing said lifts in a pile, and means for securing said lifts together to form a heel-block.

2. A heel-building machine having, in combination, means for concurrently feeding a plurality of strips of sheet material, a reciprocable straight knife for concurrently cutting polygonal lifts from the several strips, and means for superposing said lifts in a pile and securing them together to form a heel-block.

3. A heel-building machine having, in combination, means for concurrently feeding a plurality of strips of sheet material, a reciprocable straight knife for concurrently cutting polygonal lifts from the several strips, means for pasting said lifts, and means for assembling said lifts in a pile to form a heel-block.

4. A heel-building machine having, in combination, means for concurrently feeding a plurality of strips of sheet material, a reciprocable straight knife for concurrently cutting polygonal lifts of graded sizes from the several strips, means for concurrently applying paste to said lifts, and means for assembling said lifts in a pile to form a tapered heel-block.

5. A heel-building machine having, in combination, means for feeding a plurality of strips of sheet material through graded distances, a reciprocable straight knife for concurrently cutting a series of polygonal lifts of graded sizes therefrom, and means for assembling said lifts in a pile with one edge of each lift in alinement and for securing said lifts together to form a tapered heel-block.

6. A heel-building machine having, in combination, means for intermittently feeding strips of sheet material, means for cutting lifts therefrom, means for applying paste to said lifts, means for picking up said lifts, and means for depositing them successively in a pile to form a heel-block.

7. A heel-building machine having, in combination, means for intermittently feeding strips of sheet material, means for cutting lifts therefrom, means for applying paste to said lifts, means for picking up said lifts and transferring them to a delivery position, and means located below said last means when in its delivery position for causing said means to release said lifts and for collecting them in a pile.

8. A heel-building machine having, in combination, means for intermittently feeding strips of sheet material, means for concurrently cutting lifts therefrom, and means for picking up said lifts and depositing them in a pile.

9. A heel-building machine having, in combination, means for intermittently and concurrently feeding strips of sheet material, means for concurrently cutting lifts therefrom, means for applying paste to said lifts, means for concurrently picking up said lifts, and means for successively depositing said lifts in a pile in superposed relation.

10. A heel-building machine having, in combination, means for intermittently and concurrently feeding strips of sheet material, means for concurrently cutting lifts therefrom, means for applying paste to said lifts, means for concurrently picking up said lifts, and a movable member adapted to travel beneath said last means for causing said means to successively release said lifts and for collecting them in a pile to form a heel.

11. A heel-building machine having, in combination, means for intermittently and concurrently feeding strips of sheet material, means for concurrently cutting lifts therefrom, means for applying paste to said lifts, a movable collector, and means for picking up said lifts, transferring them to a position above the path of movement of said collector and successively depositing them therein to form a pile.

12. A heel-building machine having, in combination, means for intermittently and concurrently feeding strips of sheet material, means for concurrently cutting lifts therefrom, means for applying paste to said lifts, a movable member having a plurality of pickers for concurrently engaging and picking up said lifts and transferring them to a depositing position, and means traveling beneath the transferred lifts and successively cooperating with the pickers for causing them to release said lifts and for collecting them in a pile.

13. A heel-building machine having, in combination, means for concurrently and intermittently feeding a plurality of strips of sheet material, means for concurrently cutting lifts from the ends thereof, means for concurrently seizing said lifts and transferring them to a depositing position, and means for successively releasing the lifts so held and collecting them in the form of a heel-block.

14. A heel-building machine having, in combination, means for holding a row of pieces of sheet material, means for concurrently seizing said pieces and transferring them to a depositing position, and means for successively releasing said pieces and collecting them in the form of a heel-block.

15. A heel-building machine having, in combination, means for feeding strips of sheet material, means for cutting pieces therefrom, a plurality of pointed members and means for impaling the cut pieces upon said pointed members.

16. A heel-building machine having, in combination, means for feeding strips of sheet material, means for cutting pieces therefrom, a plurality of stationary pointed members, means for transferring the cut pieces into position beneath said pointed members and means for impaling said pieces upon said pointed members.

17. A heel-building machine having, in combination, means for concurrently feeding a plurality of strips of sheet material, means for concurrently cutting pieces therefrom, a plurality of stationary pickers embodying pointed members, and means for concurrently transferring said cut pieces to and impaling them upon the pointed members of the respective pickers.

18. A heel-building machine having, in combination, a support for pieces of sheet material, means embodying a plurality of pointed members adapted to be moved from a position over said support to a depositing position, means for impaling the pieces on said support upon said pointed members, and means for effecting the discharge of the pieces from said members when they occupy their depositing positions.

19. A heel-building machine having, in combination, a support for pieces of sheet material, a picker disposed above said support and embodying a plurality of pointed members, a spring-pressed stripper and a latching device for each of said pointed members, means for impaling said pieces upon said pointed members and causing said latching devices to retain the strippers in inoperative position, and means for releasing said latching devices to cause said pieces to be stripped and discharged from said pointed members.

20. A heel-building machine having, in combination, a support for pieces of sheet

material, an assembling table, a picker device for transferring the pieces from said support to said table, a parallel-motion operating mechanism for actuating said picker device from its receiving position above said support to its delivery position above said table, means for causing the pieces upon said support to be seized by the picker device in its receiving position, and means for causing said picker device to release the pieces and deposit them upon said table.

21. A heel-building machine having, in combination, means for feeding a plurality of strips of sheet material, means for cutting pieces therefrom, a support for said pieces, means for seizing said pieces, transferring them to said support and releasing them in position thereon, a picker device for seizing the pieces on said support and transferring them to a delivery position and means for causing said picker device to release said pieces in its delivery position.

22. A heel-building machine having, in combination, means for feeding strips of sheet material, means for cutting pieces therefrom, a support for said pieces, means for moving said pieces upon said support, means for raising said support and the pieces disposed thereon, and means for removing the pieces from said support.

23. A heel-building machine having, in combination, means for feeding strips of sheet material, means for cutting pieces therefrom, a support for said pieces, means for moving said pieces upon said support, means for applying paste to the pieces upon said support, means for removing the pieces from said support, and means for collecting said pieces in superposed relation.

24. A heel-building machine having, in combination, a support for a plurality of pieces of sheet material, means disposed below said support for applying paste to substantially the entire lower faces of the pieces resting thereon, and means for raising said plurality of pieces from said support and depositing them in superposed relation.

25. A heel-building machine having, in combination, a support for pieces of sheet material, means disposed below said support for applying paste to the lower surfaces of said pieces resting thereon and for raising the support and pieces disposed thereon, means disposed above said support for engaging said pieces in their raised position and removing the pieces therefrom, and means for causing said pieces to be successively deposited in superposed relation.

26. A pasting machine having, in combination, a support for pieces of sheet material, a paste-pot disposed beneath said support, a plate pivotally mounted upon said paste-pot and adapted to be rotatively immersed therein, and means for raising said paste-pot to bring the associated plate into

engagement with the lower portion of said support and the piece carried thereon.

27. A pasting machine having, in combination, a paste-pot, a movable plate mounted thereon and normally disposed above said paste-pot, means for immersing said plate into said paste-pot, and means for reciprocating said paste-pot and its associated plate.

10 28. A pasting machine having, in combination, a paste-pot, a plurality of pivotally mounted plates associated therewith, means for concurrently rotating said plates into said paste-pot for temporary immersion 15 therein, and means for raising and lowering said paste-pot and its associated plates.

29. A pasting machine having, in combination, a support for a series of pieces of sheet material, a paste-pot disposed beneath 20 said support, a plurality of separate plates pivotally mounted upon said paste-pot, means for concurrently rotating said plates to immerse them in the paste-pot, and means for reciprocating said paste-pot and associated plates to cause said plates to apply 25 paste to the lower surfaces of the pieces of sheet material disposed upon said support.

30. A pasting machine having, in combination, a supporting frame for pieces of sheet material, supporting means upon which the supporting frame normally rests, a paste-pot disposed beneath said supporting frame, a movable plate associated therewith, means for immersing said plate in the paste-pot, and means for raising said paste-pot and associated plate into engagement 35 with said supporting frame whereby paste is applied to the under surfaces of the pieces resting upon said frame and said frame is raised from its supporting means.

31. A pasting machine having, in combination, a periodically reciprocating paste-pot, a plate pivotally mounted upon said paste-pot and normally disposed above it, means for rotatively immersing said plate in said paste-pot, and means for automatically retaining said plate in its normal raised position when the paste-pot is raised 50 in position.

32. A pasting-machine having, in combination, a periodically reciprocating paste-pot, a plurality of pasting members associated therewith, means for normally maintaining said members in a position above said paste-pot and for concurrently immersing them therein, and automatic means for permitting the operation of said pasting members when the paste-pot occupies its lowered position and for locking said pasting members in their normal raised positions when the paste-pot is raised in position.

60 33. A pasting-machine having, in combination, a supporting frame for pieces of sheet material, supporting means upon which

the frame rests, a pasting device reciprocating periodically to apply paste to the pieces of sheet material upon said frame and to raise the frame above the supporting means upon which it rests, and means associated with said supporting means for guiding and determining the position of said supporting frame when it is lowered into position upon said supporting means by the pasting device.

70 34. A stock-cutting machine having, in combination, means for concurrently feeding a plurality of strips of sheet material, a series of stops against which the strips are advanced for determining their positions, means for adjusting the position of the stops at the respective ends of the series, and means mechanically associating all of the stops for adjusting the position of the intermediate stops in accordance with the adjustments of the end stops.

75 35. A stock-cutting machine having, in combination, means for concurrently and yieldingly feeding a plurality of strips of sheet material, a series of stops against which the respective strips are advanced for determining the respective lengths of the feeding movements, said lengths of movement being graded according to the sizes of the pieces to be cut from the respective strips, and means for concurrently adjusting the 80 positions of all of the stops whereby the lengths of movement of the respective strips during the feeding operation may be proportionably varied.

85 36. A heel-building machine having, in combination, an endless substantially elliptical track, a movable member guided thereby, means for actuating said member around said track, and pivotal switching means disposed near the ends of said track and operated by said movable member for effecting a substantially parallel motion of 90 said movable member throughout its travel.

95 37. A heel-building machine having, in combination, a table provided with a track, means disposed above the table for holding a row of lifts in spaced relation, and means travelling in said track for causing the holding means to successively release and drop the lifts held thereby and for collecting said 105 lifts in superposed relation in the form of a heel-pile.

110 38. A heel-building machine having, in combination, a table provided with an endless track, means disposed above the table for holding a series of lifts in spaced relation, and a channel-shaped member travelling in said track for effecting the successive release of the lifts in said holding means and for collecting said lifts in the form of a 115 heel-pile during its movement in one direction, said channel-shaped member being adapted to maintain substantially the same relative position during its movement in the opposite direction whereby the heel-pile col- 120

lected thereby, is discharged through the open side of the collector.

39. A machine having, in combination, means for feeding a plurality of laterally spaced strips of sheet material, single means for cutting a series of polygonal pieces therefrom, one from each strip, and means for superposing the cut pieces in a pile.

40. A machine having, in combination, means for feeding a plurality of laterally spaced strips of sheet material through graded distances, single means operable in a rectilinear path transversely to said strips for cutting a series of polygonal pieces of graded sizes therefrom, one from each strip, and means for assembling said cut pieces in superposed relation.

41. A machine having, in combination, means for concurrently feeding a plurality of laterally spaced strips of sheet material, single means for concurrently cutting pieces therefrom, means for concurrently applying paste to said cut pieces, and means for collecting said pasted pieces in a pile.

42. A machine having, in combination, means for feeding strips of sheet material, means for cutting a series of pieces from the ends thereof, means for picking up said pieces, and means movable with respect to the picked-up pieces for collecting said pieces in a pile.

43. A heel-building machine having, in combination, means for supporting a row of pieces of sheet material, a plurality of pointed members, one for each piece, and means for concurrently impaling all of said pieces upon said pointed members.

44. A heel-building machine having, in combination, means for producing a row of heel-lifts, a support for said heel-lifts, means for transferring said row of lifts to and depositing them upon said support, and means for removing said row of lifts from said support, transferring them to a delivery position, and effecting their delivery.

45. A heel-building machine having, in combination, means for producing a row of heel-lifts, a support for said lifts, means for moving said lifts upon said support, means for applying paste to the lifts thereon, and means for removing the pasted lifts from the support and collecting them in a heel-pile.

46. A stock cutting machine having, in combination, means for independently feeding a plurality of laterally spaced strips of sheet material, a reciprocable straight knife for concurrently cutting pieces from the ends of said strips, and means for concurrently graduating the effective feed movements of the respective independent feeding means whereby a series of pieces of graded sizes are cut from the strips.

47. A stock cutting machine having, in combination, independent means for concur-

rently and yieldingly feeding a plurality of laterally spaced strips of sheet material, means for concurrently cutting a series of pieces from the ends of the respective strips, a series of stops against which the strips are yieldingly fed for determining the positions thereof with respect to the cutting means, and means interconnecting said stops for effecting a uniformly graduated adjustment of said stops whereby a series of pieces of uniformly graded sizes are cut from the strips.

48. A heel building machine having, in combination, a movable carrier having a pointed member, means for holding heel stock in a flat condition at a point removed from carrier, means for transferring the stock while in that condition to the carrier and for forcing it on said pointed member whereby it is retained on the carrier, means for actuating said carrier from the stock receiving station to a discharge station, and means sustained by the carrier for removing the heel stock from the pointed member for deposit at the discharge station.

49. A heel building machine having, in combination, a movable carrier having a pointed member, means for impaling heel stock on said pointed member whereby it is retained on the carrier, a stock stripping device on the carrier through which the pointed member projects as stock is impaled thereon, means for actuating said carrier from the stock receiving station to a discharge station, and means for causing a relative movement between the stripping device and the pointed member to remove the stock from the latter.

50. A heel building machine having, in combination, a movable carrier having a pointed member, means for forcing heel stock on said pointed member whereby it is retained on the carrier, a stock stripping device on the carrier through which the pointed member projects as stock is impaled thereon, means for actuating said carrier from the stock receiving station to a discharge station, and means at the discharge station for causing said stripping device to advance along the pointed member and remove the stock therefrom.

51. In a heel building machine, a heel stock carrier having a stock impaling prong, a plate on said carrier having an opening through which said prong projects to impale stock, said plate being so mounted as to recede back of the free end of the prong as stock is impaled thereon, and means for relatively moving the plate and prong to discharge the impaled stock from the prong.

52. In a heel building machine, a heel stock carrier having a stock impaling prong, a plate on said carrier having an opening through which said prong projects to impale stock; said plate being movable along

the prong as stock is impaled thereon, means for latching said plate in its retracted position, and means for actuating said plate in a reverse direction to discharge the stock 5 from the prong after the latch has been tripped.

53. In a heel building machine, a heel stock carrier having a stock impaling prong, a plate on said carrier having an opening 10 through which said prong projects to impale stock, means continually tending to force said plate to a position at the free end of the prong, yet permitting a movement of the plate along the prong to impale stock thereon, and releasable means for holding said plate in its retracted position.

54. A heel building machine having, in combination, a movable carrier having a stock impaling prong, a stock stripper surrounding said prong normally at the free 20 end thereof, means for forcing stock on said prong and causing said stripper to recede back of the free end of the prong, means for holding said stripper in its retracted position, 25 means for actuating said carrier from the stock receiving station to a discharge station, and means operating after arrival at the discharge station for advancing said stripper to its normal position and thus remove the 30 stock from the prong.

55. A heel building machine having, in combination, a movable carrier having a stock impaling prong, a stock stripper surrounding said prong normally at the free 35 end thereof, means for forcing stock on said prong and causing said stripper to recede back of the free end of the prong, means for actuating said carrier from the stock receiving station to a discharge station, means 40 acting automatically to prevent advance of said stripper along the prong after the stock has been impaled and during said transfer, and automatic means for causing an advance of the stripper to the end of the prong when 45 at the discharge station whereby the stock is deposited.

56. A heel building machine having, in combination, a movable carrier having a plurality of pointed members, means for holding heel stock in a flat condition at a 50 point adjacent the carrier, for transferring said heel stock to the carrier and for impaling it on said pointed members whereby it is retained on the carrier, a stock stripping device associated with the carrier, means for advancing said carrier from the stock receiving station to a discharge station, and means for relatively moving the stripping device and the pointed members to discharge the 60 stock from the carrier.

57. A heel building machine having, in combination, a support for pieces of sheet material, a plate having a pointed member and adapted to be moved from a piece-receiving 65 position with respect to said support to a

depositing position, means for impaling a piece of sheet material upon said pointed member, means for effecting the discharge of the piece upon said pointed member at a time when it occupies its depositing position, 70 and means for securing together a number of the pieces to form a heel.

58. A heel building machine having, in combination, a movable lift carrier adapted to occupy a lift receiving station and comprising a pointed member, means for moving a lift laterally to a position beneath the carrier, means for causing relative movement between the carrier and the lift in a direction to impale the lift on the pointed 80 member, and means for pasting the under side of the lift.

59. A heel building machine having, in combination, a stock carrier, having a downwardly projecting stock impaling prong 85 forming a permanent part thereof, movable from a stock receiving station to a discharge station, means for presenting heel stock in position below said carrier and for impaling said stock on the carrier prong while at said receiving station, means for removing the impaled stock from the carrier while at said discharge station, and means for pasting the stock before it is discharged.

60. A heel building machine having, in combination, a movable carrier comprising a frame member having a pointed prong secured in fixed position thereon, means for repeatedly moving said carrier between a stock receiving station and a stock discharge 100 station, and means operating on the stock to impale it on said prong and paste its exposed surface and finally discharge the pasted stock from the carrier.

61. A heel building machine having, in combination, a movable carrier having a pointed member affixed thereto adapted to occupy a station in which lifting or other heel stock is successively positioned opposite said pointed member, means for impaling the stock on said pointed member, means for actuating the carrier to a discharge station and for discharging the stock from the carrier, and means for pasting the exposed faces of the pieces of heel stock before they 110 are discharged.

62. In a heel assembling machine, the combination of a stock carrier, a stripper plate, and a latch, said latch being constructed and arranged to hold said stripper plate in inoperative position or to permit said stripper plate to discharge a lift from said carrier according as said latch is in latched or unlatched condition.

63. In a heel building machine, a stock transferring device comprising an arm having mounted thereon a plurality of downwardly projecting impaling prongs, a stock stripping plate having apertures through which the prongs pass and a spring normal-

ly urging said plate downward whereby the plate can yield upward when the prongs are pressed downward into stock rigidly supported beneath the plate, and means for actuating said arm to transfer the impaled stock from one position to another.

64. In a heel building machine, a stock transferring device comprising an arm having a depending impaling prong rigidly secured thereto and a spring backed stripping plate associated with said prong mounted on said arm for free vertical movement relative thereto, said plate having an aperture through which said prong may pass to impale stock held below the plate upon a downward movement of said arm, and means for moving said arm and impaled stock to a new position and then raising the arm to release the impaled stock.

65. A heel building machine having, in combination, means for forming and supporting a piece of heel stock, a stock transferring device movable to a station above

said piece of stock and to a discharge station comprising an arm having a depending impaling prong rigidly secured thereto and a spring backed stripping plate associated with said prong mounted on said arm for free vertical movement relative thereto, 25 said plate having an aperture through which said prong may pass, means for moving the arm downward to engage the stock with the plate and to force the prong into the stock, and means for moving the prong in a reverse direction to free the stock after it has been 30 35 transferred to the discharge station.

66. A heel building machine having, in combination, a support for heel stock, a cutter above the support for forming stock presented thereto into pieces suitable for use as heel lifting, a device for impaling the cut pieces so produced on the support and removing them from the support, and means for applying paste to said pieces.

ERASTUS E. WINKLEY.
